UNITED STATES PATENT OFFICE.

HARRY W. PARKER, OF BROOKLYN, NEW YORK.

DESIGN FOR AN ASH TRAY.

Application filed October 22, 1927. Serial No. 23,852. Term of patent 14 years.

To all whom it may concern:

Be it known that I, HARRY W. PARKER, a citizen of the United States, residing at Brooklyn, New York city, in the county of Kings and State of New York, have invented a new, original, and ornamental Design for Ash Trays, of which the following is a specification, reference being had to the accompanying drawings, forming part thereof.

Figure 1, is a plan view of an ash tray,

showing my new design, and Figure 2 is a cross sectional view.

Figure 3, is a view of the bottom of the ash tray.

I claim:

The ornamental design for an ash tray, as shown.

In testimony whereof I have affixed my signature.

HARRY W. PARKER.
